UNITED STATES PATENT OFFICE.

JOHN OSCAR NEIKIRK, OF CHICAGO, ILLINOIS.

DRAFT-RIGGING.

No. 851,246.

Specification of Letters Patent.

Patented April 23, 1907.

Application filed July 16, 1906. Serial No. 326,419.

To all whom it may concern:

Be it known that I, JOHN OSCAR NEIKIRK, a citizen of the United States, residing at Chicago, in the county of Cook and State of Illinois, have invented certain new and useful Improvements in Draft-Rigging, of which the following is a specification.

My invention relates to draft rigging adapted to be used in any usual form of railway car; and has as an object the simplification of the construction of such devices, whereby great strength and durability is secured and the possibility of the parts of the device becoming dissembled or broken is decreased.

My invention further relates to the details of construction hereinafter described and claimed; and illustrated in the accompanying drawings, in which—

Fig. 1 is a plan of the device with the supporting members shown broken away; Fig. 2, a section of the device taken upon the line 2 of Fig. 1, showing the means of attachment to the car body; Fig. 3, a section of the device taken upon the line 3 of Fig. 1; Fig. 4, a perspective drawing of the spring-seat; Fig. 5, a sectional elevation of a preferred modification of my invention; and Fig. 6, a detail sectional view, taken upon the line 6 of Fig. 5.

In carrying out my invention—as shown in Fig. 1—I provide the slotted draft-beams *b* supported at one end upon the bolster *c* and at the other upon the end sill *d*. Extending horizontally through the slots *e*, *f*, *g* and *h*, in said draft-beams, are the metal keys *i* and *j* having secured between them the usual twin springs *k* and *l*, by means of the spring-seats *m* and *n*, which are provided with the slots *o* and *p* into which the said keys closely fit. In the usual manner I provide the inclosing yoke *q* secured at one end to the draft-bar *r* and so arranged that the spring seats *m* and *n* fit snugly against its inner shoulders at each end.

In Figs. 5 and 6 I have shown a preferred modification in which the similar draft-beams, one only of which is shown, are provided with metallic braces *s* upon their inner faces, such braces being provided with slots registering with the previously mentioned slots *e*, *f*, *g* and *h* in the draft-beams. The brace here illustrated is provided at its forward end with an upwardly extending shoulder *t* adapted to engage the end sill *d* in such manner that the forward thrust upon the

brace will be directly communicated with the end sill, and at its rearward end with the broadened portion *u* adapted to abut against the bolster to directly communicate rearward thrust, upon the draw-bar through the said brace to the bolster. This brace is also provided with extensions *v* forming an inner casting for the portion of the slots upon which the keys are adapted to slide and also forming solid shoulders for the keys, whereby the pull or thrust upon such keys is communicated directly to the end sill or the bolster, as the case may be. This brace is also rigidly secured to the draft-beams by a plurality of bolts *w* which extend through the draft-beams.

When the draft-bar *r* is placed under tension from the draft-bar of the adjacent car sufficient to overcome the normal force of the springs *k* and *l*, the key *i* is caused to slide forward in the slots *g* and *h* and the rearward end of the draw-bar is caused to slide away from its contact with the forward spring seat *m*. When the draft-bar is under compression sufficient to deflect the springs *k* and *l*, the key *i* is caused to slide rearwardly in the slots *e* and *f* and the inner face of the yoke *q* is forced from its contact with the spring seat *n* at the point *x*.

It will be noted that by this construction the strain, whether it be tension or compression, falls directly, through the medium of the keys, upon the extreme faces of the projections *v* of the brace *s* on the interior of the slots *e*, *f*, *g* and *h*, thus applying the force through the medium of such braces to the draft-beams to which the braces are tightly secured by the bolts *w*, and thence to the end sill and bolster. The braces, however, are so shaped as to also directly apply the force exerted upon them through their abutting end, the end sill and bolsters, thus furnishing very positive and rigid structure between the keys and the car body.

In this specification only such parts of the illustration have been described as it is thought necessary to clearly disclose the invention and to enable it to be practiced by those skilled in the art, and it is to be understood that certain parts herein shown and described may be of other form without departing from the scope of my invention.

I claim:

1. In a draft-rigging for railway cars, the combination with an end sill and bolster, slotted draft-beams, braces secured to such

beams and abutting the end sill and bolster and having slots therein registering with the slots in the draft-beams, keys mounted between the draft-beams and extending into the slots therein, a spring between said keys, a coupler, and means for connecting the keys to the coupler.

2. In a draft-rigging for railway cars, the combination of slotted draft-beams, keys 10 movably supported in such slots, metallic brace plates secured to the draft-beams and abutting the end sill and bolster, portions thereon extending into such slots and forming shoulders therein against which said keys 15 normally abut, a coupler, and means for transmitting the thrust upon such coupler to such shoulders.

3. In a draft-rigging for railway cars, the combination of slotted draft-beams, keys 20 movably supported within said slots, metallic brace plates secured to the draft-beams and abutting the end sill and bolster, portions thereof extending into such slots and forming shoulders and wear plates for such 25 keys, means for normally forcing the keys against such shoulders, and means for normally connecting the keys to a coupler.

4. In a draft rigging for railway cars the

combination with an end sill and bolster of, slotted draft beams, keys supported by the 30 draft beams having sliding movement in the slots, a coupler, a yoke secured to the coupler and embracing the keys, a spring between the keys and within the yoke and slotted brace plates secured to the draft beams, said 35 brace plates having at their forward ends portions abutting adjacent sides of the end sill and at their rearward ends portions abutting the bolster.

5. In a draft rigging for railway cars, the 40 combination with end sill and bolster, of slotted draft beams secured thereto, slotted metallic brace plates secured to the draft beams and formed with portions extending into the slots in the draft beams and upwardly extending end portions abutting the end sill and bolster, keys carried by the brace plates and having sliding movement in the slots therein, a coupler, a yoke secured to the coupler and embracing the keys, spring seats 45 50 secured to the keys within the yoke, and a spring between such spring seats.

JOHN OSCAR NEIKIRK.
